OYSTER HARVESTING APPARATUS

Joseph Michel Jurisich, New Orleans, La.

Application July 6, 1943, Serial No. 493,652

2 Claims. (Cl. 37—55)

This invention relates to means for harvesting oysters from oyster beds in coastal waters and other usual situations, and has for an object to provide an extremely simple apparatus for this purpose which will have novel features of construction, particularly in the conveyor and means for disengaging the oysters from their supports in the oyster beds.

It is an especially important aim of the invention to provide a device which will be liable in a minimum degree to damage from submerged heavy articles, and which will have raking devices so constructed that they will function effectively, yet will be sufficiently yielding to avoid damage or strain to the mechanism, and at the same time may be readily replaced and renewed as required.

It is a related important aim of the invention to enable the replacement or renewal of the raking members without requiring a complete renewal of the actual conveyor parts or heavy mechanism of the device.

A further aim of the invention is to present a construction of harvester which will automatically adapt itself to variations in depth of the water in which it operates, while delivering the harvest to a barge or the like afloat. It is also an important aim of the invention to present an apparatus of the kind which may be readily mounted upon any usual ship or barge structure suitable for loading with oysters without interfering with usual vessel-propelling means, steering devices and the like.

Additional objects, advantages and features of invention reside in the construction, arrangement and combination of parts involved in the embodiment of the invention, as will be apparent or understood from the following description and accompanying drawings, wherein

Fig. 1 is a side elevation of a harvester machine constructed in accordance with my invention.

Fig. 2 is a detail of the delivery end of the harvester formally illustrated as mounted upon a steel barge.

Fig. 3 is a similar view of the gathering end of the harvester.

Fig. 4 is a detail cross section of a conveyor structure.

Fig. 5 is a fragmentary plan view thereof.

Fig. 6 is a detail elevation of one of the raker devices in one embodiment.

Fig. 7 is a detail elevation in section of a modified form of the raker device.

There is illustrated a portion of a barge 10, conventionally shown, and which may be of wood 55

or steel construction, or other conventional forms (not illustrated), and may include any usual means of propulsion and steering, details of the latter two features not being illustrated since they involve no essential novel parts of the present invention.

While my conveyor device may be operated by any conventional power take-off or other operative connection from the usual marine power plant for the propulsion of vessels, in the present instance I have illustrated a Diesel motor 11, mounted upon the bottom of the hull of a barge, with a reduction gearing 12 of conventional form, operating a main drive sprocket 13, by which the conveyor of my invention is driven by means of heavy drive chain 14. In the present instance, the barge is illustrated with vertical hull sides, and secured to these at each side of the barge there are heavy structural steel legs 16, widely separated on their bases at each side, inclined toward each other upwardly, where they are joined by conventional gusset plates 17, in which a main axle or shaft 18 is mounted horizontally, extending between the two frames thus constructed at each side of the barge. Upon the shaft 18 at each side of the framework, there are mounted radius frames 20, comprising upper and lower guide bars 21 and 22, joined by a gusset plate 23 suitably pivoted upon the shafts 18 to support one end of the radius frame pivotally. At the lower and outer end of this radius frame, it rests upon a sliding sledge, represented in the present instance as a heavy channel iron runner 24 at each side, upon which respective sets of forward and rearward bracket plates 26 and 27 are erected, the former two carrying therebetween a shaft 28 upon which gusset plates 29, similar to the plates 23, are pivoted, the plates 29 connecting the lower ends of the guide bars 21 and 22 of the radius frame. The rearward brackets 27 support an axle 30 upon which a harvesting drum 31 is revolvably mounted, to one end of which a suitable sprocket 32 is secured by which it may be driven through the agency of a chain 33 from the conveyor now to be described, and a conventional reversing gearing 33', on bracket 27.

The conveyor comprises two sprocket-drums 34 mounted on the shafts 18 and 28, respectively, the driving chain 14 being engaged with the upper one, while the driven chain 33 to the drum 31 is engaged with the lower one, as illustrated in Figs. 2 and 3, respectively. The conveyor proper consists of a link belt construction of approved form, the link elements of which are suitably spaced and arranged to form a grid deck, the inter-

stices of which will permit mud and the like and small particles to drop through, while supporting and carrying oysters of proper size.

Upon each link unit 35' of the belt, a transverse plate 35 is secured, extending the full width of the belt, which may be four feet in width, more or less, as discretion may dictate. Upon each of these plates there are secured a plurality of flexible loops 36, preferably of steel wire cable; five-eighths of an inch cable having a loop which extends outward from the conveyor approximately eight inches being contemplated in the present instance. While the cable is relatively flexible, nevertheless, when formed in loops of the size indicated, it will resist bending to such extent that the loops, when raking against an oyster bed, will exert considerable force, sufficient to loosen oysters and draw them upwardly from the beds, as will be subsequently indicated. The loops may be secured to the plates 35 by removable clamp plates 37, by which the ends of the loops are anchored firmly upon the cross plates 35.

As indicated in Fig. 6, the cross plates, as at 35'', are provided with pairs of apertures 38 through which the ends of the loops are inserted and turned laterally under the plate, and the clamp plates 37' are drawn upwardly against the laterally turned ends of the loops by a bolt 39 engaged through the plate 37' and screwed into the plate 35''.

As shown in Fig. 4, however, the clamp plates 37, each of rectangular oblong shape, are spaced apart approximately three inches for the size of loops indicated, and having a central aperture to receive a bolt 40 therethrough to screw into the plate 35. The ends of the cable are inserted downwardly through the apertures 38' and turned laterally, and the plate 37 then set over and clamped against the respective cross plate 35 by means of the bolt 40, substantially as shown. The plate 35 may be secured upon the conveyor by being welded to respective sets of transversely aligned links of the conveyor, or otherwise, as found expedient. The drum 31, like the conveyor, is provided with a closely spaced series of transverse plates 35a, upon which cable loops 36 are secured in the same manner as upon the conveyor, and the drum is preferably spaced in such relation to the lower bracket drum 34 of the conveyor as to afford a space between the conveyor and the drum sufficient to permit passage of oysters incident to operation of the machine, as will be described.

The height of the bracket 27 supporting the drum is such that the lower periphery of the drum lies in very close relation to the oyster bed or bottom 46 of the stream or other body of water in which the apparatus is operated. Also, the mounting of the shaft 28 in the brackets 26 is such as to bring the lower end portion of the conveyor into close relation to the bottom 46 upon which the sledge is moved.

The length of the radius frame 20 may be proportioned to the depth of water in which the device is to be used, some extensive beds being in comparatively shallow water, while others are located at greater depths, but the size of the loops 36 and the diameter of the drum 31 may be approximately the same for all situations, although compensation may be made for oysters of uniformly small size, such as are found in some localities.

The apparatus may also be found useful for harvesting clams, mussels, sponges, kelp, or other

materials, especially materials which it is desirable not to break or bruise unduly in harvesting.

It should be noted that the lower guide bar 22 of the radius frame 20 is spaced further from the shafts 18 and 28 than is the upper bar 21. In consequence the lower reach of the conveyor may be supported on the bar 22 while descending, as shown, preventing objectionable sagging of this part of the conveyor. The upper reach of the conveyor ascends while slidably supported on the upper bar 21, the ends of the bars 35 extending laterally of the conveyor link units so as to rest on the bars 21 and 22, as mentioned.

The chute 25 extends under the upper end of the conveyor sufficiently to catch all material delivered by the conveyor, and serves as protection for the motor 11 in part in the present instance if the latter is located as illustrated. The barge may also be provided with a decking or other conventional protection, not shown, as may be found desirable.

It will be seen that in order to restore or renew one of the loops 36, it is only necessary to loosen the bolt 40 at the particular loop requiring repair or replacement, and the ends of a loosened loop than reinserted through the plate 37 and the latter again clamped to the plate 35 by screwing in the bolt 40, or a new loop put in place as before described after removal of damaged cable ends. In this way only those loops which become damaged need be moved, without disturbing any other parts of the conveyor, and without removal of any other loops on the same plate 35.

In the use of this apparatus, the conveyor framing being installed upon a barge or other vessel arranged for being drawn by a towing vessel or equipped for self-propulsion with the conveyor and sledge support trailing therebehind and suitable driving connections with the conveyor being made, as the barge progresses, the loops 36 of the conveyor move rearwardly in engagement with oysters upon the bottom 45, while the loops upon the drum 31 sweep forwardly upon the bottom 45 with a movement faster than that of the loops upon the conveyor. The oysters are caught in the loops or before the sides of the loops which are advancing in either direction against the bottom 45, and drawn in the direction of such relative movement of the loops upon the bottom and upwardly. Those oysters moved by the drum 31 are thrown upon the conveyor, and either before or after such delivery to the conveyor are caught by the loops of the conveyor and finally carried upwardly to the barge, as indicated. The convergent movement of the loops of the conveyor and those of the drum 31 causes the opposed loops to cooperate in lifting the oysters between the conveyor and drum, and the greater speed of the drum at its periphery as compared with the rate of travel of the conveyor, causes the material carried by the drum to drag against the rear sides of the loops of the conveyor, so that the oysters carried upon the loops of the drum will be dragged off and caught by the conveyor. Centrifugal force developed in the oysters themselves, and by water passing radially outwardly from the drum will also contribute to discharge of the oysters onto the conveyor, so that none will be carried upwardly and rearwardly over the drum 31.

The speed of movement of the conveyor and the drum in functioning as described and particularly that of the drum are preferably not such as to hold oysters pressed in the loops of the drum too firmly to prevent ready disengagement

and movement to the conveyor, as will be appreciated. The drum 31 may consist of two simple foraminous circular heads, one at each side, across which bars 35 are secured without intervening parts corresponding to the link elements 35', so that a clearway is afforded between the bars 35 for ready movement of water, and in the operation of the drum there will be a certain degree of outward movement of water between the bars due to centrifugal action, which will tend to clear the drum of material carried thereby, as may be understood.

While I have described the details of the best construction of the apparatus of my invention at present known to me, it will, nevertheless, be understood that various modifications may be made in the construction, arrangement, and combination of parts, substitution of materials and substitution of mechanical equivalents which the experience of those versed in oyster dredging may indicate, or which the mechanical requirements of the machine may dictate, without departing from the spirit of the invention, except as may be more specifically indicated in the claims hereinafter appended.

As shown in Fig. 1, there is provided a sprayer 5, the objective of which is to surge water onto the oysters carried on the upper chain into the barge, thus flushing the dirt off of the oysters back into the water bed. This shower head may be located at any convenient point on the upper chain. However, if it is near the upper sprocket 20 a baffle or diverter plate can be placed over the barge to direct the washing water back into the water bed.

In the embodiment of the raker device shown in Fig. 7, there are secured upon each of the conveyor plates a plurality of open end cables 36a, preferably made of steel wire, usually $\frac{3}{8}$ to $\frac{5}{8}$ of an inch in diameter. The bent end of each cable member is secured between the cover plate 37a and the bed plate of the link 38a by means of a bolt or cap screw 39a.

It is desired to point out that optimum conditions are obtained by having every set of alternate longitudinal links made of open loops, shown in Fig. 7, and closed loops, shown in Fig. 6, the objective being that the actual digging or lifting will be done by the open end cables while the picking up will be performed by the closed loop cables. In other words, the loop shown in Fig. 6 has a pick-up action and the members shown in Fig. 7 has a digging, excavating or unearthing action. While either form of the raking device may be used by itself, the best results are obtained by the combination, as described.

What is claimed is:

- 15 1. A harvester of the character described consisting of a floating support, an inclined conveyor having one end mounted thereon for vertical pivotal movement thereon, a sledge in supporting relation to the outer end of the conveyor, a drum mounted revolvably on the sledge in close spaced relation to the outer end of the conveyor, and a multiplicity of sweep devices upon the drum at least, each consisting of a short loop of resilient material of limited flexibility, and releasable means to hold each loop in operative position.
- 20 2. Harvesting apparatus of the character described comprising a floating support, a trailing conveyor frame pivoted thereon for vertical movement at its outer end, an endless conveyor thereon, runners adapted for sliding movement upon a marine bottom supporting the outer end of the conveyor, means to operate the conveyor, a rotary drum mounted on said runners outwardly of the conveyor, operative connections between the conveyor and the drum, sweep members comprising flexible loop devices mounted on said drum, and a multiplicity of similar sweep devices mounted on said conveyor and arranged to intermesh and cooperate with those of the drum.
- 25 30 35

JOSEPH MICHEL JURISICH.
